UNITED STATES PATENT OFFICE.

GEORGE M. KURNALIAN, OF TROY, NEW YORK.

FOLDING-MACHINE.

1,333,085.

Specification of Letters Patent. Patented Mar. 9, 1920.

Application filed July 27, 1918. Serial No. 247,060.

To all whom it may concern:

Be it known that I, GEORGE M. KURNALIAN, a subject of Turkey, residing at Troy, county of Rensselaer, and State of New York, have 5 invented certain new and useful Improvements in Folding-Machines, of which the following is a specification.

Reference may be had to the accompanying drawings, and the reference characters 10 marked thereon, which form a part of this specification. Similar characters refer to similar parts in the several figures therein.

This invention relates to folding-machines of various kinds such for example as machines for inturning the edges of textile blanks in the manufacture of collars, etc.

The principal object of the invention is to inform the operator of the machine of the number of blanks turned or the number of 20 operations of the machine.

Other objects will appear in connection with the following description.

Figure 1 of the drawings is a view in front elevation of the upper portion of the folding machine with a portion broken away and shown in section.

Fig. 2 is a view in elevation of the right-hand end of the machine shown in Fig. 1.

Fig. 3 is a view in front elevation of the 30 counting-device detached.

Fig. 4 is a view in rear elevation of the same.

Fig. 5 is a top plan view of the same with the casing partly broken away, and shown 35 in section.

Fig. 6 is a view showing the interior of the body of the casing of the counting-device, and the parts mounted thereon, the rear cover being removed.

Fig. 7 is a similar view of the detached rear cover of the casing of the counting-device with the parts mounted thereon.

Fig. 8 is a view in rear elevation of the 45 counting-device complete detached from the machine.

Referring to the drawings wherein the invention is shown in preferred form, 1 is the frame of a folding machine, such as is used for inturning the edges of blanks in the 50 manufacture of collars and the like.

The machine has a bed or table, 2, adapted to support a blank during the folding operation.

A die, 3, is mounted upon a die-head, 4, 55 carried by an oscillatory arm, 5, pivoted at

6, upon a bracket, 7, in fixed relation to the frame of the machine, whereby the die-head, 4, and die, 3, are adapted to be swung toward and from the bed, 2, the die, 3, resting upon the blank on the bed during the folding 60 operation.

The arm, 5, may be actuated by means of a link, 8, connected with any suitable source of power in the usual manner.

Infolders, 9, are movable inwardly and 65 outwardly over the bed, 2, and serve to inturn the edges of the successive blanks over the edges of the die, 3. The infolders may be moved inwardly or outwardly in any known manner.

The parts thus far described are commonly used in folding machines and their construction and manner of operation will be readily understood so that further description of these parts, as well as the general operation and construction of the machine, will be unnecessary.

In carrying out my invention in its preferred form, I mount upon the die-head, 4, by means of a screw-attached clip, 10, a 80 counting-device of which 11 is the body of the casing for the device, and 12 is the rear cover for same, secured to the body, 11, by screws, 13.

The casing also has a front cover, 14, 85 screwed to the body by means of screws, 15.

Upon the front cover is mounted a dial, 16, numbered from 1 to 24, adapted to be read in connection with an index, 17, operated by a ratchet-wheel, 18, mounted within 90 the body of the casing.

The ratchet-wheel, 18, is engaged by a pawl, 19, carried by a rod, 20, adapted to reciprocate longitudinally in slideways, 21, mounted on the inner side of the front cover, 95 14, of the casing.

A coil-spring, 22, tends to resist upward movement of the rod, 20.

The rod, 20, extends downwardly out through an opening, at 23, in the bottom of 100 the casing-body to a point substantially beyond the bottom surface of the die, 3, as shown in Fig. 2.

The parts are so arrested that each upward movement of the rod, 20, will through the medium of the pawl-and-ratchet mechanism impart to the index, 17, a rotative movement from one dial member to the next successive dial member.

The rod, 20, thus projects downwardly 110

from the die at a point within the general contour of the die, whereby it is adapted to engage a blank resting on the bed during the folding operation.

5 The portion of the bed covered by the blank during the folding operation is provided with an opening, 24, opposite the point where the rod, 20, engages the bed-supported blank into which opening, 24, the 10 end of the rod, 20, idly passes when no blank is supported upon the bed.

In the operation of the machine when no blank is supported upon the bed the counting-device and the rod, 20, will be moved in unison with the die-head toward and from the bed, but the rod, 20, will idly enter the opening, 24, and the counting-device will 15 not be actuated.

When however, a blank is supported upon 20 the bed and the die-head is moved toward the bed to force the die down upon the blank the downward movement of the rod, 20, will be arrested by its engagement with the blank causing a relative upward movement of the 25 rod, 20, with respect to the ratchet-wheel, 18, thereby causing the pawl, 19, to operate the index, 17.

Operations of the machine for purposes 30 of experiment or adjustment without the use of blanks will not thus be registered by the counting-device, and only the actual turning of the blanks will be registered.

Should it be desired to operate the machine at times upon blanks without registering the operations on the counting-device, the rod, 20, may be secured in raised position as indicated by dotted lines, 25, in Fig. 8, by means of a set-screw, 26, which may be screwed into tight engagement with the upper end of the rod, 20, which projects from the top of the casing.

As the principal object of the invention is to make it unnecessary for the operator to count the blanks after they have been 45 folded and to avoid mistakes in counting, I preferably provide the counting-device with a signal bell, 27, or other audible signal which is automatically sounded upon the folding of the last of a predetermined number of blanks.

The counting-device may be designed for sounding such a signal upon the folding of the last of any predetermined number of blanks.

55 As illustrated, I have shown a cam, 28, fixed upon the ratchet-wheel, 18, adapted at each 24th step-by-step movement of the index, 17, to release a trip, 29, carrying a hammer, 30, which when released rings a bell, 27, the bell being mounted upon the outer side of the rear casing-cover, 12, and

the trip, 29, being pivotally mounted at 31, upon the inner side of said cover.

A coil-spring, 32, serves to actuate the hammer, 30, when the trip is released from 65 engagement with the cam, 28.

The operator thus need pay no attention to the number indicated by the index, 17, as he will be informed by the ringing of the bell that twenty-four blanks have been 70 folded by the machine.

For certain purposes of the invention any known form of counting-device may be employed which has an operating member idly movable into the opening in the bed when 75 no blank is present, and which is caused to operate the counting-device when its movement into said opening is prevented by a blank covering the opening.

While I have described my invention in 80 its preferred application to folding machines, it will be apparent that the invention may be applied to any machine operating upon blanks of various kinds, such as collar blanks, cards and the like wherein 85 the blank to be operated upon by the machine covers the opening in the bed, and causes the counting-device to be operated by preventing an operating member of the counting-device from entering said opening. 90

What I claim as new and desire to secure by Letters Patent is—

1. In a folding machine, the combination with a bed provided with an opening in a blank-covered portion of the bed; a die-head movable toward and from the bed; a counting device mounted upon the die-head and movable therewith toward and from the bed, said counting-device having an operating member adapted to idly enter said opening in the bed in the absence of a blank on the bed, and caused to actuate the counting-device when the movement of said member is arrested by engagement with a blank on the bed preventing the entrance of said 100 member into said opening.

2. In a folding machine, the combination with a bed provided with an opening in a blank-covered portion of the bed; and a die-head movable toward and from the bed; of a counting-device actuated by pawl-and-ratchet mechanism, having a pawl-carrying rod which enters said opening in the bed when no blank is present on the bed, and which actuates the pawl-and-ratchet mechanism when the movement of said rod toward the bed is arrested by a blank on the bed covering said opening.

In testimony whereof I have hereunto set my hand this 16th day of July, 1918.

GEORGE M. KURNALIAN.
